UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

PACKAGE AND METHOD OF MAKING THE SAME.

Application filed July 3, 1924, Serial No. 723,960, and in Argentina September 8, 1922.

My invention relates to a package and the method of making the same.

The object of my invention is to produce a neat, securely closed and inexpensive package, and provide a method by which such a package may be made expeditiously and accurately. The details of my invention will appear as the description proceeds.

In the accompanying drawing, Figure 1 is a diagrammatic view illustrating the method of producing my package; Fig. 2 is a side view of a portion of Fig. 1; Fig. 3 is an end view of the completed package.

In carrying out my process I use an elongated tube 10 of suitable bag material. This tube is longitudinally collapsed at 11, so that a considerable length of it may be stored in a storage zone about a feed tube 12. The feed tube 12 is shown with a hopper 13 at its upper end, and a flattened portion 14 at its lower end. External contacting means, such as coil spring 15, are used to prevent the bag from being drawn down off of the feed tube prematurely.

In carrying out the process the lower end of the tube is drawn down, as at 10^a, and a charge of material is fed into the hopper 13 and dropped through the feed tube into the lower end 10^a, which has been previously closed. After the charge has been filled into the lower end 10^a, the tube is collapsed so as to bring its walls together immediately above the charge, and four reinforcing tapes 16, 17, 18 and 19 are fed across the tube where it is collapsed.

These tapes are fed from storage means diagrammatically indicated on Fig. 2 as spools 20, 21, 22 and 23. Seams 24 and 25 are sewn by needles 26 and 27 longitudinally of the tapes and through the interposed collapsed tube walls, so as to form reinforced closures for the bag ends. As will be seen, the upper end of the filled bag is closed at the same time that the lower end of the unfilled tube is closed, and the tube between these reinforced closures is severed along a line 28 by cutting means diagrammatically indicated at 29. This cutting means is preferably located immediately back of the needles, so as to insure the line of severance being parallel with the seams.

Preferably, a series of tubes are used so that closures may be formed across adjacent tubes in succession, and in Fig. 1 additional tubes 101 and 102 are indicated at the right

of tube 10. The tapes are fed continuously across these adjacent tubes and the seams are sewed continuously longitudinally of the tapes, so that the reinforced seams continue across the spaces between the adjacent tubes, as at 30 and 31, between tubes 10 and 101.

In Fig. 1, the lower ends 151 and 152 of tubes 101 and 102 have been filled and completely closed and severed from the upper portions of the tubes and the reinforced seam between the portions 151 and 152 has been severed at 32 so as to disconnect the package 152 from the packages in process of formation.

The reinforced seam connecting the bottoms of the tubes 10, 101, 102, etc., may be severed at the same time that the corresponding reinforced seam connecting the tops of the packages is severed, as at dotted line 33 in Fig. 1. Where this is done the lower ends of the tubes may be manipulated independently, which is sometimes preferable. If desired, the severance of the reinforced seam connecting the bottoms of the tubes may be postponed until after they are filled. On Fig. 1 the reinforced seam 17' is indicated as connecting the bottoms of the tubes until the packages have been completely formed, although it is optional as to whether this be done or the seam be previously severed, as at dotted line 33'. It is evident that to separate the completed package from the packages in process of formation, the seam 17' must be severed, as at 34, if it has not been previously severed.

In the form of package shown, the walls of the tube are collapsed so that they meet along a single plane, as indicated at 35 on Fig. 3. This is advantageous as it results in a seam of nearly uniform thickness throughout its length, but in its broader aspects my invention is not confined to that manner of collapsing the bag walls.

It is evident that the reinforced seams, formed in the manner described, will extend beyond the walls of the package at each side, as at 36 and 37, at the upper end, and at 38; 39, 38' and 39', at the lower end, of the package.

A cheap bag, and one which is satisfactory for most purposes, may be made by using paper tubes and paper reinforcing strips, and that is my preferred material, but other materials may be used.

Where the tube is made of such materials

as paper, the line of perforations formed by the needle weakens the walls of the bag, and this weakening of the line of closure is accentuated by the strain which the drawing of the thread against the sides of the paper between the stitches necessarily produces. The reinforcement substantially eliminates this strain of the thread on the material between the perforations and so strengthens the line of closure as to prevent the closure from being materially weaker than other portions of the package walls.

Where cloth is used for the bag, it is customarily sized to prevent sifting of packaged materials through the meshes of the cloth, but the perforations of the needle and the manipulation to which the cloth is subjected along the line of the seam frequently dislodges the sizing and opens the pores of the cloth, so that leakage of the contents of the bag results. A reinforcing strip is, therefore, advantageous in connection with the closure of cloth bags.

The best results are obtained by using a reinforcing strip on each side of the seam, as shown and described, but some of the benefits of the reinforced seam may be realized with but one reinforcing strip. This is especially true where a one-thread seam is used and the loops of the thread are positioned on the opposite side of the seam from the reinforcing strip, the reinforcement being more necessary on the side which the needle enters in forming this type of seam.

In closing packages which are arranged in series, it is advantageous to sew a continuous seam across successive packages, and the use of a reinforcing strip or strips progressively positioned in front of the advancing seam has a number of advantages:

(a) Extending the reinforcing strips across the spaces between packages insures the continuous efficient operation of the stitching mechanism and prevents dropping of stitches and faulty "chaining out" between packages;

(b) The presence of the reinforcing strips between packages makes proper spacing of the packages more simple and severing of the seam or chain at desired distances from the sides of the packages more accurate;

(c) The continuation of the reinforcing strips between the spaced ends of the packages and the location of the seams therein prevent the ravelling of the ends of the seams;

(d) Where a strip is progressively positioned across the bag immediately in advance of the advancing seam, it may be so positioned that the seam will follow the desired line along the strip, which is generally midway between its edges; thus, the maximum benefits of the reinforcing strip may be realized with a minimum of material, and the resultant package presents a much more

pleasing appearance than would a package in which the reinforcing strips were wider and the seam followed an irregular line along the same.

(e) If the strips were placed on the tubes or package walls before they were filled, they would not only interfere with the feeding of the tubes from the storage zone, but when the tube or package walls were brought together, it would be extremely difficult to bring the reinforcing strips exactly opposite each other and they would therefore have to be wider in order to insure the seam being sewed through the two strips; also the resultant seam would be likely to follow a somewhat irregular line along the reinforcing strips and could not well follow along the central line of both strips.

The formation of parallel seams and subsequent severance of the tube walls between the reinforced closures results in bag ends parallel with the reinforced seams. This parallel relation of the bag end to the reinforced seam insures an extension of the bag material beyond the line of closure sufficient to provide for strength of the closure, without necessitating the use of excess material at any point, and also results in a neater appearance than would result from a bag end not parallel with the closing seam.

While the process has been described in connection with the formation of filled bags from bag tubes, it is not confined as to all features to that process. Many of the advantages of the process of forming bag closures may be realized when closing the mouths of filled bags that have been formed and filled in any desired manner, and some features of the process are applicable to forming closures for empty bags.

The described process may be modified in various other particulars, within the scope of the appended claims, without departing from the spirit of the invention.

What I claim is:

1. The process which consists in positioning a continuous reinforcing strip across a series of spaced bag ends, forming bag end closures reinforced by the strip, and severing the strip in each space between bag ends after the strip is secured to the bags adjacent that space.

2. As a new article of manufacture, a bag comprising a tube, a reinforcing member extending transversely across the end of said tube, and a stitched seam passing through the tube and said reinforcing member and closing the end of the tube, said reinforcing member and line of stitching extending laterally beyond the tube on each side.

3. As a new article of manufacture, a bag comprising a tube, reinforcing members extending transversely across the end of said tube on opposite sides thereof, and a stitched seam passing through the tube and said re-

inforcing members and closing the end of the tube, said reinforcing members and line of stitching extending laterally beyond said tube on each side.

5 4. As a new article of manufacture, a package comprising a paper tube, the walls of the tube being collapsed at the end thereof so that their surfaces contact each other along a single plane only, flat paper reinforcing strips extending transversely across

the end of the tube on each side thereof parallel with said plane, and a stitched seam passing through the end of the tube and centrally through the strips and closing the end of the tube, said reinforcing strips and seam extending laterally beyond the tube on each side.

In testimony whereof I have hereunto subscribed my name to this specification.

ADELMER M. BATES.
